(57) **CLAIM**

The ornamental design for a audio and image digital file transfer device, as shown and described.

DESCRIPTION

FIG. 1 is a perspective view of an audio/video data file transfer device showing our new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.

The broken lines, which define the bounds of the claimed design form no part thereof.

The broken lines environmental are for illustrative purpose only and form no part of the claimed design.
